Primary Examiner—Antoine Duval Davis
Attorney, Agent, or Firm—Michael W. Ferrell[57] **CLAIM**

The ornamental design for a flange pattern for a disposable food serving bowl, as shown.

DESCRIPTION

FIG. 1 is a view in perspective showing a flange pattern for a disposable food serving bowl having a flange pattern in accordance with the invention;

FIG. 2 is a top plan view of the bowl of FIG. 1;

FIG. 3 is a view in elevation of the bowl of FIG. 1; and, FIG. 4 is a bottom plan view of the bowl of FIG. 1. A portion of the disclosure of this patent document contains material to which a claim for copyright is made. The copyright owner has no object to the facsimile reproduction by anyone of the patent document or the patent disclosure as it appears in the Patent and Trademark Office patent file or records, but reserves all other copyright rights whatsoever.
